UNITED STATES PATENT OFFICE.

RALPH G. TAYLOR, OF DAVENPORT, IOWA, ASSIGNOR TO BETTENDORF AXLE COMPANY,
OF BETTENDORF, IOWA, A CORPORATION OF IOWA.

OPERATING MECHANISM FOR CAR-DOORS.

1,026,230.

Specification of Letters Patent.

Patented May 14, 1912.

Application filed October 26, 1910. Serial No. 589,108.

To all whom it may concern:

Be it known that I, RALPH G. TAYLOR, a citizen of the United States, residing at Davenport, in the county of Scott and State of Iowa, have invented new and useful Improvements in Operating Mechanism for Car-Doors, of which the following is a full, clear, and exact description.

My invention relates to mechanism for closing and controlling the discharge opening of the hoppers of dump-cars, and particularly, of the convertible flat-bottomed freight car and dump-car described in the copending application of William P. Bettendorf, deceased, Serial No. 589,096, filed October 26, 1910 (Case 189).

The object of my invention is to provide simple and economical means for closing the doors of these discharge openings, which can be easily operated by one person, which will hold the doors in any position desired, without the necessity of ratchets or brakes, and which can operate two doors at once. This, I accomplish by the means hereinafter fully described, and as particularly pointed out in the claims.

In the drawings: Figure 1 is a side elevation of a portion of a dump-car embodying my improvements. Fig. 2 is a vertical longitudinal section through one of the hoppers of the same drawn to a slightly larger scale. Fig. 3 is an underneath view of the hopper portion of the car. Fig. 4 is a transverse vertical section, taken on dotted line 4, 4, 35 Fig. 1 and drawn to a slightly larger scale. Fig. 5 is a slightly enlarged vertical section through the discharge end of a hopper with portions of the door broken away to show the coupling between the connecting rod and 40 cross-beam.

In the drawings A represents the body of a metal car, which is provided with an underframe consisting of the usual parts, including a center-sill B, needle-beams C. D. and hoppers, E. In the application of William P. Bettendorf, deceased, hereinbefore referred to, the car is shown to possess two corresponding alining and opposed hoppers on each side of the center-sill, that are arranged so as to discharge toward the center of the car below the plane of the center-sill. Two of these hoppers are in the same transverse planes, and as the only difference in the construction between this pair, whether located on one side of the center of length of

the car or the other, is that one is right and the other left, a brief description of one will suffice.

Each hopper has a long sloping bottom portion, a, that inclines toward the center of the car, the lower edge of which terminates in a suitable plane mediate the underside of the center-sill and the rails, and has short sloping portions b, that incline in opposite directions from the center of length 65 toward the ends of the car, whose lower edges terminate about midway the height of the center-sill. The inner side-wall is vertical and has the parts of its lower edge coterminous with the said sloping bottoms 70 flanged laterally under said bottoms and riveted thereto, and has the outer wall inclined inwardly from the side-sills to which its upper edge is secured, and its lower edge flanged under the said bottom-portions a, 75 and b, riveted thereto. The portion of the edges of the side-walls between the lower edges of the long and short inclined edges of the hopper are straight and complete the discharge-opening of said hopper. The 80 edges of this discharge-opening are suitably reinforced and it is closed by a door G, which, preferably, consists of a single plate of sheet metal shaped so as to close said opening, and having its edges flanged outward. These doors are hung by means of 85 hinges, d, d, to the underside of the shorter inclined bottom portion of the hopper near its lower edge. The weight and pressure upon this door is considerable when the car is loaded, and my improvement relates to the means for regulating and controlling the closure of this door. To accomplish this, I provide the doors G, G, of each pair of hoppers with a bracket e, consisting, 90 preferably, of a flat strip of sheet metal bent somewhat into the shape of a U, one of whose legs is shorter than the other, and with its end edges flanged outward. When this bracket is secured to the outer surface 95 of each door with the shorter leg uppermost, its most advanced portion will be almost vertical. An I-beam H, of suitable length has its ends riveted or otherwise secured to this advanced portion of the bracket, and 100 transversely passing under the center-sill connects one door with the other door of the pair. Immediately under the center-sill this I-beam is clamped between the attaching plates f, f, of a coupling; each of said 105 110

plates having a projecting lug I, that has an eye extending there-through parallel to the plane of the web of said I-beam. The screw-threaded ends of a V-shaped yoke or clevis J are extended through the eyes of said coupling lugs, and secured to the latter by means of nuts h, h. Now, the doors G are kept closed or partially or wholly opened, according as desired, by means of 10 a worm K on a revoluble transverse worm-shaft, k, a worm-gear L, and a suitable connecting-rod M. The worm-shaft k, is journaled in bearings in hangers m secured to and depending from the needle-beam D, and 15 one end thereof projects through its bearings, and has a hand-wheel on its outer extremity with which to turn it. The worm-gear L is driven by worm K, and is arranged horizontally and journaled on a 20 suitable stud projecting down from a supporting-plate n secured to the underside of the center-sill. The connecting-rod, M, has an eye at one end that links with clevis J, and is bifurcated at its other end to enable 25 it to pass both above and below the worm-gear. These bifurcations, o, o, have their ends crooked slightly and pivotally connected to a crank-pin, Q, that is secured in and projects on both sides from the worm- 30 gear. Now, the worm gear, the connecting-rod and the doors are so assembled with relation to one another that when the worm gear is turned through the medium of the worm and worm-shaft, the door will be 35 opened or closed and held in any position desired without the necessity of a pawl and ratchet. The friction between the worm and worm gear is in itself sufficient to prevent any lost movement. At the same time, 40 the leverage that can be exerted by the worm and worm gear, is such that one man can have perfect control of the doors.

What I claim and desire to secure by Letters Patent is:

45 1. A dump-car, comprising a hopper depending below the plane of the underframe and having a discharge-opening therein, a door for closing said discharge-opening, a worm, the axis of which is arranged transversely of the car, a horizontally disposed worm-gear actuated thereby, a connecting-rod, pivotally connected to said gear at one end, and means connecting it to the door at the other end.

50 2. A dump-car, comprising a hopper depending below the plane of the underframe and having a discharge-opening therein, a door for closing said discharge-opening, a worm, the axis of which is arranged transversely of the car, a horizontally disposed worm-gear actuated thereby, a connecting-rod having one end bifurcated and pivotally connected to said gear, and means connecting it to the door at the other end.

55 3. A dump-car, comprising a hopper de-

pending below the plane of the underframe and having a discharge-opening therein, a door for closing said discharge-opening, a worm, the axis of which is arranged transversely of the car, a horizontally disposed worm-gear actuated thereby, a connecting-rod pivotally connected to said gear at one end, a transverse bar or beam secured to said door, one end of which projects beyond the side edge of the same, and a yoke for connecting it to the door at the other end.

4. A dump-car, comprising two hoppers arranged one on each side of the center of width of the car, and depending below the plane of the underframe, and having discharge-openings therein, a door for closing the said opening of each hopper, a transverse member connecting said doors, a worm, whose axis is transverse of the car, a horizontally disposed worm-gear actuated by said worm, a connecting-rod disposed between said hoppers and pivotally connected to said worm-gear at one end, and adapted to impart the motion of the same to said transverse member.

5. A dump-car comprising two hoppers arranged one on each side of the center of width of the car, and depending below the plane of the underframe, and having discharge-openings therein, a door for closing the said opening of each hopper, a transverse member connecting said doors, a worm whose axis is transverse of the car, a horizontally disposed worm-gear actuated by said worm, a connecting-rod disposed between said hoppers, and pivotally connected to said worm-gear at one end, and a yoke connecting the opposite end of said connecting rod to said transverse member.

6. A dump-car comprising two hoppers arranged one on each side of the center of width of the car, and depending below the plane of the underframe and having discharge-openings therein, a door for closing the said opening of each hopper, an I-beam connecting said doors, a worm, whose axis is transverse of the car, a horizontally disposed worm-gear actuated by said worm, a connecting-rod disposed between said hoppers and pivotally connected to said worm-gear at one end, and a coupling clamped to said I-beam between said hoppers, and a yoke or clevis connecting said connecting-rod to said coupling.

7. A dump-car comprising two hoppers arranged one on each side of the center of width of the car, and depending below the plane of the underframe and having discharge-openings therein, a door for closing the said opening of each hopper, an I-beam connecting said doors, a worm, whose axis is transverse of the car, a horizontally disposed worm-gear actuated by said worm, a connecting-rod disposed between said hoppers and pivotally connected to said worm-

gear at one end, and a coupling consisting of two plates clamped to the web of said I-beam mediate said hoppers, and having lugs projecting therefrom, and a yoke, the 5 ends of which extend through and are secured in perforations in said lug, and which connects said connecting rod and coupling.

8. A dump-car comprising two hoppers arranged one on each side of the center of 10 width of the car alongside of each other that depend below, and have discharge-openings below the plane of the underframe of the car, a hanging door for each of said discharge openings, a bracket secured to and 15 projecting from each of said doors, a transverse I-beam having its ends secured to said brackets, a transversely arranged worm, a horizontally disposed worm-gear actuated thereby, and a connecting-rod for imparting 20 motion from said worm-gear to said I-beams and doors.

9. A dump-car comprising two hoppers

arranged one on each side of the center of width of the car alongside of each other that depend below, and have discharge-openings 25 below the plane of the underframe of the car, a hanging door for each of said discharge-openings, a bracket secured to and projecting from each of said doors, a transverse I-beam having its ends secured to said brackets, a transversely arranged worm, a horizontally disposed worm-gear actuated thereby, a coupling secured to said I-beam mediate said hoppers, a yoke, or clevis, the 30 ends of which are secured to coupling, and 35 connecting-rod connecting said worm-gear and yoke.

In witness whereof I have hereunto set my hand this 18th day of October, 1910.

RALPH G. TAYLOR.
